US00D945248S

(12) **United States Design Patent** (10) Patent No.: **US D945,248 S**
Sendin et al. (45) Date of Patent: **** Mar. 8, 2022**

(54) **LOCK**

(71) Applicant: **OJMAR, S.A.**, Elgoibar (ES)
(72) Inventors: **Richard Sendin**, Elgoibar (ES); **Julien Boullie**, Elgoibar (ES)

(73) Assignee: **OJMAR, S.A.**, Elgoibar (ES)

(**) Term: **15 Years**

(21) Appl. No.: **29/688,958**

(22) Filed: **Apr. 25, 2019**

(30) **Foreign Application Priority Data**

Oct. 26, 2018 (EM) 005809860-001
Feb. 21, 2019 (EM) 006263695-001
